[57] CLAIM

The ornamental design for a garden tool, as shown and described.

DESCRIPTION

FIG. 1 is a perspective view of the garden tool of my invention;

FIG. 2 is a front elevational view;

FIG. 3 is a side elevational view;

FIG. 4 is a top plan view; and,

FIG. 5 is a bottom plan view.

The rear elevational view is the same as the view shown in FIG. 2.

The elevational view from the other side of the claimed design is the same as the view shown in FIG. 3.

The broken line showing of tines is for illustrative purposes only and forms no part of the claimed design.
